SLIPPER

Maurice N. Brower, Leonia, N. J., assignor to Gustave, Inc., New York, N. Y., a corporation of New York

Application February 16, 1950, Serial No. 7,958

Term of patent 3½ years

(Cl. D7—7)

To all whom it may concern:

Be it known that I, Maurice N. Brower, a citizen of the United States, residing at 478 Broad Avenue, Leonia, New Jersey, have invented a new, original, and ornamental Design for a Slipper, of which the following is a specification, reference being had to the accompanying drawing, forming part thereof, in which:

Fig. 1 is a top plan view of a slipper, showing my new design; and

Fig. 2 is a side elevational view thereof.

I claim:

The ornamental design for a slipper, substantially as shown.

MAURICE N. BROWER.
